UNITED STATES PATENT OFFICE.

ROBERT SCORER AND ROBERT HAM, OF TROY, ASSIGNORS TO JORDAN L. MOTT, OF NEW YORK, N. Y.

DESIGN FOR A PARLOR-STOVE.

Specification forming part of Design No. 6,305, dated December 17, 1872.

To all whom it may concern:

Be it known that we, ROBERT SCORER and ROBERT HAM, of the city of Troy, in the county of Rensselaer and State of New York, have jointly invented and produced a new and original Design for Parlor-Stoves, of which the following is a specification, reference being had to the accompanying wood-cut or engraving of a parlor-stove which embodies our said design.

One part of our invention consists of the design for the skeleton cover A of the water-urn, as shown in the aforesaid wood-cut. Another part consists of the design for the removable plate B upon which the urn is mounted, as distinguished by the word "Tropic" formed and arranged thereon so as to appear substantially as represented in the aforesaid engraving. Another part consists of the design for the top-plate C, as distinguished by the fluted upper part d, in combination with the ornamented middle and outer parts e f, substantially as represented in the cut or engraving. Another part consists of the design for the upright section G, as distinguished by the curved top-panels having the net-work ornamentation h thereon and surmounted by the ornaments i, so as to appear substantially as shown in the aforesaid cut. Another part consists of the design for the frames J for the mica-lights, as distinguished by the hinge-shields k, base l, columus m, and top piece n, all shaped,

arranged, and ornamented so as to appear substantially as shown in the engraving. Another part consists of the design for the base-section O, as distinguished by the rows of ornaments p, shaped and arranged on the inclined surface thereof so as to appear substantially as shown in the engraving. Another part consists of the design for the removable hearth-plate Q, with or without the hinged part r thereon, and shaped and ornamented as shown in the wood-cut.

What we claim as our invention is—

1. The design for the cover A of the urn, as set forth.
2. The design for the base-plate B of the urn, as herein specified.
3. The design for the top plate C, as described.
4. The design for the upright section G, as set forth.
5. The design for the mica-light frames J, as described.
6. The design for the base-section O, as described.
7. The design for the hearth-plate Q, as set forth.

ROBERT SCORER.
ROBERT HAM.
